UNITED STATES PATENT OFFICE.

RALPH J. WELLS, OF DAYTON, OHIO.

RAILWAY-TRACK CONSTRUCTION.

Application filed August 6, 1925. Serial No. 48,510.

My invention relates to railway ties and more particularly to a further improvement of the construction disclosed in my copending applications for Letters Patent, Serial 5 No. 693,000, filed February 15, 1924, since matured into Patent No. 1,528,999 dated March 10, 1925, and Serial No. 7,909, filed February 9, 1925. Whereas both prior constructions referred to contemplate the employment of a resilient body of semifluid or plastic character necessitating the employment of a receptacle or container to confine the cushion material, the present invention differs therefrom by utilizing a solidified 10 form of resilient cushion material which will readily retain its form until embedded in the concrete road bed or other support, thereby eliminating the necessity for a special receptacle.

20 In the present construction there are contemplated spaced blocks of resilient material, such as asphalt intermixed with a filler of asbestos, saw dust or other fibrous or granular material enabling the asphalt material 25 to be molded into form retaining bodies, such blocks being interconnected by transversely arranged tie bars to which the blocks are connected by bolts which also serve to secure top plates or sleeper plates of metal 30 resting upon the blocks of resilient material, and the track rails which rest upon the plates. The assembled skeleton tie is suspended from the track rails over the excavated road bed or otherwise supported in 35 elevated position, and plastic concrete is poured around and beneath the tie structure, thus embedding the spaced blocks and tie bars therein.

In pouring the concrete about the resilient 40 supporting blocks and tie bars, the blocks form their own cavities or recesses in the concrete body which conforms closely and accurately to the blocks.

The molded blocks are confined to such 45 cavities or recesses of the concrete body by the overlying sleeper or top plates which form closure lids therefor. The molded bodies of resilient material which are not sufficiently resistant to withstand the pressure, shock and vibration of traffic over the 50 supported track, without distortion and disintegration, though sufficiently strong to hold their form while being embedded in the concrete, are thus confined within the concrete body against displacement, distortion,

or change of form. The cover plate may be a simple flat plate of metal, but is preferably, though not necessarily, peripherally flanged to fit over and enclose the top margins of the molded resilient block. This 60 sleeper plate being embedded substantially flush with the top surface of the concrete body effectually prevents the oozing or escape of the resilient material from the recesses or pockets formed in the concrete. 65

The object of the invention is to simplify the structure as well as the means and mode of installation of such railway ties, whereby they will not only be cheapened in construction, but will be more efficient in use, of increased durability and wearing qualities, compact in form, accommodating an increased quantity of cushion material and unlikely to get out of repair. 70

A further object of the invention is to 75 insure the resilient material being closely confined in the concrete body by making the concrete body conform closely and accurately to the body of resilient material embedded therein. 80

A further object of the invention is to facilitate the manufacture and also the installation of such ties.

With the above primary and other incidental objects in view as will more fully appear in the specification, the invention consists of the features of construction, the parts and combinations thereof, and the mode of operation or their equivalents, as hereinafter described and set forth in the 90 claims. 85

In the accompanying drawing wherein the preferred, but obviously not the only form of embodiment of the invention is shown, Fig. 1 is a transverse sectional view of a 95 track installation employing the tie forming the subject matter hereof. Fig. 2 is a perspective view of the tie structure, one end being disassembled to show more clearly the component parts. Fig. 3 is a longitudinal 100 sectional view through one end of the tie. Fig. 4 is a transverse sectional view thereof. Fig. 5 is a view similar to Fig. 3 but illustrating the use of a simple flat sleeper plate in lieu of a flanged top plate. 105

Like parts are indicated by similar characters of reference throughout the several views.

While the tie construction forming the 110 subject matter hereof may be employed for

open track installation, or in cross country trackage, in which event the skeleton tie structures will each be embedded in a separate elongated body of concrete, it will find its greatest field of usefulness at the present time in urban construction, wherein the ties are embedded in a continuous concrete foundation or road bed. The primary purpose of this tie, as well as the previous constructions referred to, is to afford the requisite degree of resiliency, which will not only improve traffic conditions but will absorb the shock and vibration and so prevent breakage and disintegration of the concrete subbed. The tie in such installation becomes in effect a transverse reinforcement member for the concrete foundation or road bed. So long as the concrete road bed remains intact it functions as a single enlarged sleeper or support which distributes traffic pressure throughout the entire width of the road bed. If subjected to ordinary traffic shocks and the impact of car wheels, such concrete road bed is liable to more or less breakage and disintegration. The skeleton structure of the present tie, not only serves to reinforce and tie together the concrete road bed, enabling it to resist breakage, but the resilient blocks at opposite ends of the tie structure upon which the sleeper plates supporting the track rails rest, serve to cushion and absorb the shocks and vibration thereby protecting the concrete foundation against such breakage and disintegration. The blow or impact of the car wheels upon an unyielding track structure is as detrimental to the rolling stock as it is to the track itself. The cushioning effect of the present construction is equally as advantageous in protection of the railway equipment as it is of the track itself.

Referring to the drawing, 1-1 indicates two metallic angle bars arranged in parallel spaced relation with their horizontal flanges inwardly directed one toward the other. Located adjacent to the opposite ends of the bars 1 and resting upon the inturned flanges are resilient blocks 2-2. These blocks are formed from any suitable resilient material. The most suitable and practical for commercial production at the present time is asphalt intermixed with a suitable filler, such as asbestos, saw dust, marble dust or other material which will form with the asphalt a form retaining mixture. This mixture is preferably such that it may be molded in blocks, either under pressure or in the presence of heat. The essential idea is to give to the body sufficient rigidity to enable it to be assembled in the skeleton tie and to be handled in shipment and installation without breaking, yet without destroying its resiliency when under load. The quantity of filler and decreased resiliency is somewhat compensated for by making the block of

greater thickness than the stratum of semi-fluid asphalt employed in the constructions before referred to.

The top of the block 2 is preferably chamfered to receive the marginal flanges 3 of the recessed cap or sleeper plate 4. The marginal edges of the sleeper plate 4 are substantially flush with the sides and ends of the resilient block 2. In lieu of providing a recessed cap or sleeper member 4, a simple flat metallic plate 5 agreeing in length and width with the dimensions of the block may be employed as shown in Fig. 5.

The block and sleeper are interconnected with the angle bars 1-1 by bolts 6 extending through corresponding holes in the respective members. The same bolts 6 carry at their upper ends clamp members 7 for securing the track rails 8 to the tie structure. The completely assembled ties are supported over the road bed at the established grade, and a body of concrete 9 is poured around and beneath the skeleton ties embedding such tie structures in the concrete body. A convenient method of installation successfully employed is to attach the track rails directly to the ties with the ties properly spaced, and then level the track rails at the established grade upon temporary supports while the concrete is being deposited. The preformed blocks 2 of resilient material form cores around which the concrete flows, thus making the concrete and resilient bodies conform accurately to each other, and the body of resilient material accurately and completely fills the pocket or recess thus formed in the concrete body. The sleeper plates 4 and 5 being the same size as the blocks of resilient material, also accurately fit the pockets or recesses in the concrete for which they form closure lids to prevent the escape of the resilient material. Alone the blocks 2 would not support the weight of traffic nor withstand the shocks incident thereto. However once embedded in the concrete they are confined and supported against distortion, and are so enabled to yieldingly support the imposed weights and pressure and withstand the shocks. The sleeper plates being supported wholly by the enclosed body of resilient material and independent of the concrete are free for slight vibratory movement vertically against the yielding resistance of the confined body 2. Fitting closely within the recess in the concrete body the sleeper plates effectually prevent the oozing of the material even in warm weather and under heavy traffic pressure. One of the difficulties encountered in the early attempts to employ asphalt or like material for cushioning effects in railway ties was the tendency for the material to ooze out of the receptacle when subjected to heavy pressure. This tendency was especially preva-

lent during warm weather. By utilizing the resilient body and the sleeper plate as a core and pouring the concrete thereabout, a much more accurate fit is insured than could possibly be commercially produced otherwise.

While the present tie possesses the advantages of those structures described in the aforementioned applications for Letters Patent, it may be produced at less cost by the elimination of the pan or receptacle necessary when a semi-fluid body of asphalt is employed.

While asphalt intermixed with inert matter is described as the preferable resilient material, it is to be understood that other material possessing the requisite characteristics of being resilient, and retaining its form under ordinary conditions, may be substituted. Also while angle bars afford a convenient form of stock material readily obtainable for interconnecting the blocks and forming the reinforcement, other shapes of bars or tie rods may be employed.

From the above description it will be apparent that there is thus provided a device of the character described, possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect, and the invention is, therefore, claimed in any of its forms or modifications within the legitimate and valid scope of the appended claims.

Having thus described my invention, I claim:—

1. In a railway track construction, a plurality of spaced blocks of resilient material having insufficient strength to withstand traffic impact shocks, but being sufficiently strong to retain their form during investment in a body of concrete, tie bars connecting the blocks in pairs, sleeper members resting upon the spaced resilient blocks, and a body of concrete molded in situ about said blocks and bars wherein the blocks are utilized as cores which form in the concrete body recesses to which the blocks of material conform, said sleeper members being supported by the embedded resilient blocks independent of other supporting means.

2. In a railway track construction, a body of concrete, molded bodies of resilient material having sufficient solidity to retain their

form while being embedded in the concrete but insufficiently resistant to retain their form, when unconfined, under the pressure of passing traffic, recesses formed in the concrete body within which the blocks closely conform, and sleeper plates resting upon the embedded bodies of resilient material independent of other supporting means.

3. The herein described method of railway track construction, consisting in pre-forming blocks of resilient material having the characteristics of solidified asphalt, employing such preformed blocks as cores, pouring a body of concrete about said cores and in intimate contact therewith, to insure close confinement of the resilient cores within the concrete body, resting sleeper members upon said embedded cores and supporting track rails upon the sleeper members.

4. The herein described method of railway track construction consisting in providing bodies of resilient material of such consistency as to retain their forms during encasement but normally insufficiently strong to resist traffic pressure when unconfined, utilizing said bodies as cores and pouring a body of self hardening material thereabout in direct contact with said cores thereby embedding the cores in close conformity with the surrounding body, resting sleeper members upon said cores and supporting track rails upon said sleeper members.

5. In a railway track construction, tie bars arranged transversely of the track structure, sleeper plates interconnected in spaced relation with the tie bars, preformed bodies of resilient material interposed between the tie bars and sleeper plates and utilized as cores in the formation of a concrete body thereabout, and a body of concrete poured in situ about said core blocks and in direct contact therewith in which said resilient core blocks and tie bars are embedded, and track rails supported upon said sleeper plates.

6. In a railway track construction, track rails, sleeper plates upon which the track rails rest, tie bars interconnecting the sleeper plates one with another in pairs, bodies of resilient material located beneath the sleeper plates and a body of concrete in which the bodies of resilient material are embedded.

7. In a railway track construction, a plurality of preformed bodies of resilient material interconnected one with another having the characteristics of solidified asphalt, and utilized as cores in the formation of a concrete body thereabout, a body of concrete poured in situ about said core blocks and in direct contact therewith, in which the resilient core blocks and their interconnections are embedded, and track rails supported by the inserted core blocks.

8. In a railway track structure, a rail

rest including a preformed block of resilient material of insufficient tensile strength to alone withstand the pressure of traffic passing over the rail, and a body of concrete or the like molded in situ about said block as a core, whereby the molded body closely conforms to the shape of the core block and confines said block against distortion and disintegration under traffic pressure upon the rail which is supported upon said block.

9. In a railway construction of the character described, a body of concrete having a pocket formed therein, a body of resilient material substantially filling the pocket, and a metallic sleeper plate resting upon the body of resilient material and extending below the surface of the concrete body forming a closure for the pocket free for vibra-

tory movement against the yielding resistance of the material within the pocket and independent of engagement with the concrete body, said sleeper plate in turn supporting a track rail.

10. In a railway construction of the character described, a body of concrete having a pocket formed therein, a filling of resilient material within the pocket, and an inverted pan shaped sleeper plate enclosing the upper portion of the filling of resilient material and extending within the pocket for free vertical vibratory movement independent of the concrete body.

In testimony whereof, I have hereunto set my hand this 3rd day of August A. D. 1925.

RALPH J. WELLS.
